UNITED STATES PATENT OFFICE.

WILLIAM A. RINGLER, OF PHILADELPHIA, PENNSYLVANIA, ASSIGNOR TO GLOBE
WERNICKE CO., OF CINCINNATI, OHIO, A CORPORATION OF OHIO.

VISIBLE INDEX

Application filed April 14, 1923. Serial No. 632,097.

To all whom it may concern:

Be it known that I, WILLIAM A. RINGLER, a citizen of the United States, residing at Philadelphia, county of Philadelphia, State 5 of Pennsylvania, have invented a new and useful Visible Index, of which the following is a specification.

My present invention comprehends a novel construction and arrangement of a visible index in which the index strips are contained within a novel construction and arrangement of index holders so that when the parts are assembled with the frame, the entire contents of the index are visible at a 10 glance and the number of holders and index strips can be reduced in number or added to without disarranging the alphabetical or numerical sequence of the indices.

It further comprehends a novel construction of a visible index wherein the transparent holders are formed in a novel manner in order that they can be detachably connected with the frame and in order that when in the frame the holders can be interlocked with juxtaposed holders.

Other novel features of construction and advantage will hereinafter more fully appear in the detailed description and the appended claim.

For the purpose of illustrating my invention, I have shown in the accompanying drawings embodiments thereof which are at present preferred by me, since these embodiments will be found in practice to give satisfactory and reliable results. It is, however, to be understood that the various instrumentalities of which my invention consists can be variously arranged and organized and that my invention is not limited to 35 the precise arrangement and organization of these instrumentalities as herein shown and described.

Figure 1 represents, in perspective, an index holder and index strip of a visible index, embodying my invention.

Figure 2 represents, in front elevation, a portion of the visible index.

Figure 3 represents a section on line 3—3 of Figure 2.

Figure 4 represents, in perspective and in detached position, another form of card holder, embodying my invention, in conjunction with an index strip.

Figure 5 represents, in front elevation, a portion of a visible index having an index

or card holder corresponding to that seen in Figure 4.

Figure 6 represents a section on line 6—6 of Figure 5.

Figure 7 represents a similar section but 60 showing the holders interlocked in a different manner from that seen in Figure 2.

Similar numerals of reference indicate corresponding parts.

Referring to the drawings.

Referring first to the embodiments seen in Figures 1, 2 and 3, 1 designates a holder of a visible index, embodying my invention. This holder is formed of sheet material which is transparent such as, for example, celluloid. The blank from which the holder 1 is formed is bent to form the front face 2 and then at its bottom is upwardly deflected to form the intermediate flap 3, the blank being then bent downwardly to form the 70 locking flap 4. In this manner, a slot or groove 5 is formed, the walls of which are substantially parallel with the ends of the slot open, so that an index strip 6 can be readily inserted by simply sliding it into 75 position either longitudinally or laterally with respect to the holder 1. The index strip 6 can be made of paper or any other desired material and is adapted to have indicated thereon any desired data such as, for example, names and addresses.

The intermediate flap 3 terminates between the top and bottom faces of the front face 2 and the back 4 extends a desired distance below the termination of the bottom 90 of the front face 2 in order to form a locking flap which forms with the intermediate flap 3 a pocket 7. The manner in which the parts interlock will be understood by reference to Figure 3 from which 95 it will be understood that the pocket 7 receives the upper portion of the index strip and front face 2 of the holder below it while the locking flap 4 extends below and overlaps the upper portion of the flap 4 100 which is positioned below it. In this manner, the card holders interlock with each other and the names and addresses or other data which is on the lower portion of the index strips 6 will be readily visible. The 105

holders are assembled within a frame 8 having the inturned marginal flanges 9 which form guides to receive the ends of the holders 1. The holders and the index strips are flexible so that by bending them 110

one end can be inserted in one guide and then the other end in the other guide, it being understood that the holders and their cards or index strip are slidably carried by the frame so that they may be individually removed and replaced whenever desired.

In the embodiments seen in Figures 4 to 7 inclusive, the frame and the index strips are of the same construction and 10 have therefore been identified by similar reference characters as are used in the embodiments seen in Figures 1, 2 and 3.

In this embodiment seen in Figures 4 to 7 inclusive, 10 designates a holder which is 15 formed from transparent material such as, for example, celluloid, and instead of having one locking flap, as shown in Figure 1, it is provided with a plurality of locking strips. The blank of sheet material from 20 which the holder 10 is formed is bent to form a front transparent face 11 from the upper face of which the blank is bent downwardly, as indicated at 12, and then upwardly to form the upper locking flap 13. 25 At the bottom edge of the flap 11 the blank is bent upwardly, as at 14, and then downwardly to form the lower locking flap 15. In this manner, a pocket 16 is formed, the 30 rear walls of which converge inwardly while the front face 11 is flat. The index strip 6 has the desired data placed thereon and is then inserted in the pocket 16, as will be understood by reference to Figure 4. The 35 holders 10 with their index strips 6 are then assembled with the frame so as to be slidable therein, the ends of the holders being retained in position by the inturned guide forming flanges 9 of the frame. Juxtaposed holders may be interlocked with 40 the flaps in the manner shown in Figure 6 or in the manner shown in Figure 7. The portions 12 and 13 form between them an annular pocket 17 and the portions 14 and 15 form between them an 45 annular pocket 18. When the parts are assembled, however, the walls of these pockets become substantially parallel. As seen in Figure 6, the holders can be inter-

locked so that the locking flap 13 will be received in the pocket 18 of the superposed 50 holder while the bottom flap 15 will be received in the pocket 17 of the next lower holder.

In the embodiment seen in Figure 7, the 55 holders are assembled so that the upper flap 13 overlaps and is in rear of the lower flap 15 of the superimposed holder while the lower flap 15 is received in the pocket 17 of the holder positioned beneath it.

In both the embodiments of my invention as herein shown, the holders have 60 pockets to receive the intake strip, the ends of such pockets being closed when the 65 holders are in assembled position in the frame. As the front face of each holder is transparent, the subject-matter on each 70 index strip will be readily visible and at the same time the index strips are protected so that there is no chance of their collecting dirt, dust or foreign material. 70

It will now be apparent that I have devised a new and useful visible index which embodies the features of advantage enumerated as desirable in the statement of the invention and the above description, and 75 while I have, in the present instance, shown and described embodiments thereof which will give in practice satisfactory and reliable results, it is to be understood that the same are susceptible of modification in 80 various particulars without departing from the spirit or scope of the invention or sacrificing any of its advantages.

Having thus described my invention, what I claim as new and desire to secure by 85 Letters Patent, is:

An index support for a visible index, comprising a strip of transparent material folded to form a pocket to receive the index and deflected in opposite directions to extend above and below said pocket to thereby 90 form an upper and a lower locking flap.

WILLIAM A. RINGLER.
